(57) **CLAIM**

The ornamental design for a top toy, as shown and described.

DESCRIPTION

FIG. 1 is a perspective view of a top toy showing my new design;

FIG. 2 is another perspective view thereof;

FIG. 3 is still another perspective view thereof;

FIG. 4 is the other perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom view thereof.

The broken lines illustrate portions of the top toy that form no part of the claim.

1 Claim, 10 Drawing Sheets
